GAS RANGE

William D. Antrim, Gloucester, N. J., assignor to
 Roberts & Mander Stove Company, Philadelphia, Pa., a corporation of Pennsylvania

Application October 12, 1934, Serial No. 748,149

2 Claims. (Cl. 126—39)

This invention relates to new and useful improvements in gas ranges and more particularly to improvements in the construction of the oven casings thereof adjacent the burner intake.

The principal object of the invention is to provide a gas range having an oven which is novelly constructed at the burner intake to effectually balance the pressure or vacuum at the intake and outlet respectively of said burner and prevent extinguishment of the burner flame.

Other objects and features of the invention as well as the details of construction thereof are set forth hereinafter and shown in the accompanying drawings, in which:

Fig. 1 is an elevational view in section through the oven of a gas range on line 1—1, Fig. 2.

Fig. 2 is an elevational view in section on line 2—2, Fig. 1.

Fig. 3 is an end view of the mixing chamber of the burner.

Fig. 4 is a view in perspective showing the construction of the burner support and air inlet.

Fig. 5 is a view in perspective of a modified form of support for the end of the mixing tube of the burner; and

Fig. 6 is a view in section of another modification of the invention.

As constructed heretofore, the oven burner is usually located in the chamber under the oven and the heated gases pass therefrom into and about said oven. Consequently when the oven door is opened quickly, a pressure or vacuum is formed in the oven and burner chamber, which tends to draw air through the mixing tube and into the burner thus thinning the mixture of gas and air and in some cases causing a flame to be produced at the intake end of the mixing tube. So too, if the oven door is closed quickly, the air in the oven is obviously placed under pressure and this pressure is very often sufficient to extinguish the flame, particularly when the same is burning low. These difficulties are obviously troublesome and may at times prove to be extremely dangerous.

By the present invention the undesirable characteristics mentioned above are eliminated, and the pressure or vacuum existing within the burner chamber is effectively balanced at the intake and outlet of the burner, thereby eliminating any possibility of a so-called flash back or extinguishment of the burner flame.

Referring now more particularly to the drawings, reference numeral 1 indicates the casing of an oven structure, having inner walls or lining 2 spaced from said casing as clearly shown in Fig. 1.

The casing in the present instance encloses relatively superimposed chambers A and B constituting respectively an oven and a burner chamber. As shown in the drawings plates 3, bent to form a series of supports 4 for the customary oven racks (not shown), cooperate together with a bottom plate 5, to form the oven within the casing 1, the plates 3 being spaced from the inner walls 2, 2 of the oven and having openings at the top thereof to afford communication between the burner chamber B and the interior of the oven A, and openings are formed in the oven roof and allow the combustion gases to escape through a suitable conduit extending toward the rear of the oven casing for connection with a flue (not shown). A plate 6 is secured to the underside of the oven bottom 5 in spaced relation with respect thereto so as to prevent the flame from the burner impinging directly upon said plate 5.

A bottom section 7 is mounted at the lower end of the casing 1 in spaced relation with respect to the plate 5 and constitutes the bottom of the burner chamber B. The bottom section 7 is supported upon angle bars 8 secured to the casing 1 at one side thereof and to a front flame member 10 of the oven on the opposite side as clearly shown in Fig. 2, the said bottom section 7 and angle bars 8 being so arranged to provide air inlet openings 8a to the burner chamber. The side walls of the burner chamber B are provided with supports 11 for the customary grill or broiler rack (not shown). In the present instance the front of the casing 1 is open and is provided with a door or other closure 12 which, as shown in Fig. 2, is hingedly connected to one wall of said casing, and affords ready access to the interior of both the oven and burner chamber.

A burner 13 having a mixing tube 14 open at its front end 15 is mounted horizontally within the chamber B of the casing substantially midway between the bottom of the oven and the grill or broiler rack supports 11. Gas is conducted to the burner 13 by means of a pipe 16 leading from any source of supply and preferably located between the casing 1 and the inner wall or lining 2 thereof. The pipe 16 is connected to a nozzle 17 forming a part of the burner 13 and extending a short distance into the mixing tube 14 thereof. An opening or air inlet 18 is provided in the forward end of the mixing tube 14 and the amount of air admitted through said opening for mixture with the gas may be readily regulated and controlled by the usual damper 19.

The outer end of the mixing tube 14 of the burner 13 is supported at a recess in the chamber 55

wall by a flange 20 projecting from a ring 21 which forms a part of a plate 22 secured to the lining or inner wall 2 of said casing by any suitable means such as bolts 23. In order to carry 5 out the present invention it is desirable that the edge of the supporting flange 20 continuously contact the peripheral surface of the outer end of the mixing tube 14 of the burner 13 for the purpose of preventing the passage of air to or from 10 the burner chamber B between the ring 21 and the end of the burner supported thereby. To facilitate regulation of the damper 19 to control the mixture of gas and air in the burner an opening 24 is formed in the casing 1 directly in 15 front of the end face of the burner tube 14. This opening 24 is normally closed by means of an imperforate cap 25 which is removably secured in the casing 1 by means of a spring clip 26 secured to the said cap and which engages the 20 inturned flanges 27 on the casing 1.

As shown in Fig. 1 of the drawings, partitions 28 extending between the casing 1 and the inner wall or lining 2 thereof form a recess in the side wall and enclose the space between the opening 25 24 in the casing and the end of the mixing tube, the said partitions being arranged so that the recess or pocket thus formed extends a substantial distance below the said end of the mixing tube and said opening. The partition 28 at the top of the 30 space between the opening and the end of the mixing tube 14 is cut away to allow for the passage of the gas supply tube 16.

In the present instance a relatively large opening 29 is formed in the plate 22 below the ring 35 21 thereof for the purpose of affording communication between the enclosed space or recess previously described and the chamber B below the plane of the burner 13 mounted therein.

It will be readily perceived that construction 40 of the oven casing at the intake end of the burner in accordance with the present invention prevents the entrance of fresh air into the burner through the side walls of the casing and requires that all of the air necessary for mixture with the 45 gas in the mixing tube 14 of the burner pass through the opening 29 from a point or points below the burner. In this manner the pressure or vacuum at the intake and outlet respectively of the burner will at all times be in perfect balance, and therefore differential pressures or vacua 50 at the intake or outlet of the burner causing flash back or extinguishment of the burner flame will be entirely eliminated.

The construction of the oven casing previously 55 described is susceptible of numerous ramifications without departing from the spirit of the invention and for the purpose of illustration a modification of the invention is disclosed in Fig. 5 of the drawings wherein the end of the mixing tube of the 60 burner is mounted in a ring 21a of a plate 22a. The upper half portion of the circular ring 21a is provided with a downwardly projecting flange 20a, the edge of which is arranged to continuously contact the adjacent outer surface of the 65 end of the mixing tube of the burner and prevent communication throughout its extent be-

tween the space at the front of said burner and the chamber B, whereas the bottom of the end of the burner is supported in spaced relation from the ring 21a by means of a finger or arm 29a for the purpose of providing openings 29b for communication between the space at the front of the burner and the chamber B below the plane of said burner. 5

The present invention may be readily adapted to existing gas range constructions wherein the 10 intake end of the burner mixing tube 14 is mounted in an opening 30a in the oven casing 1, to permit air from without the oven casing to be supplied to the mixing tube in the customary manner heretofore. In the adaptation of the present invention to this construction, an opening 30 is formed in the oven wall structure below the intake end of the mixing tube 14 as shown in Fig. 6 and this opening 30 and the intake end of the mixing tube 14 of the burner are enclosed by 20 means of a cover or casing member 31 which is hingedly connected as at 32 to the oven casing 1 to form a recess at one side wall of the casing similar in nature to that previously described. In this manner it will be readily perceived that air 25 entering the intake end of the mixing tube 14 for mixture with the gas fuel must pass through opening 30 from a point below the burner, thereby effectively balancing the pressure or vacuum existing at the intake and outlet respectively of 30 the burner.

Still other casing constructions may be adopted to effectually carry out the invention, and while several forms thereof have been set forth for the purpose of description it is not intended that the 35 invention be precisely limited thereto within the scope of the annexed claims.

What I claim is:

1. The combination in a gas range structure 40 of an oven; a burner chamber arranged in communication with said oven; a burner in said chamber; a mixing tube extending into said chamber and being connected to said burner; and means supporting the inlet end of said tube in predetermined spaced relation to a wall of the 45 structure; said means comprising a supporting plate attached to said wall and having a flange thereon directed into the burner chamber, said flange being provided with an inwardly directed flange for supporting the inlet end of said tube 50 at the periphery thereof.

2. The combination in a gas range structure 55 of an oven; a burner chamber arranged in communication with said oven; a burner in said chamber; a mixing tube extending into said chamber and being connected to said burner; and means supporting the inlet end of said tube in predetermined spaced relation to a wall of the 60 structure; said means comprising a supporting plate attached to said wall and having a flange thereon directed into the burner chamber, said flange being provided with an inwardly directed flange and a radially extending arm for supporting the inlet end of said tube at the periphery thereof. 65

WILLIAM D. ANTRIM.
